UNITED STATES PATENT OFFICE.

JAMES IRVING MUNDELL, OF GROTON, CONNECTICUT.

PLANER MACHINE.

Application filed July 9, 1923. Serial No. 650,396.

To all whom it may concern:

Be it known that I, JAMES I. MUNDELL, a citizen of the United States, residing at Groton, in the county of New London and 5 State of Connecticut, have invented a new and useful Planer Machine, of which the following is a specification.

This invention aims to provide a planer mechanism carrying clapper blocks, so 10 mounted that the tool in one block will operate when the work is moved in one direction, the tool in the other block operating when the work moves in an opposite direction, the planer cutting thus on both strokes. Another 15 object of the invention is to provide novel means for feeding the tools in various directions with respect to the work.

It is within the province of the disclosure to improve generally and to enhance the 20 utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown 25 can be made without departing from the spirit of the invention.

In the drawings:

Figure 1 shows in horizontal section, a portion of a planer embodying the present 30 improvements, parts being broken away; Figure 2 is an elevation showing a portion of the vertically adjustable frame which moves on the housing; Figure 3 is a section on the line 3—3 of Figure 1; Figure 4 is a section on the line 4—4 of Figure 1. Figure 40 5 is a plan showing the driving mechanism for the planer table; Figure 6 is an elevation of the driving mechanism for the planer table.

The numeral 1 marks the vertical posts which constitute a part of the housing of a planer. The numeral 2 designates, generally a frame mounted for vertical adjustment on the posts 1, the frame embodying 45 side members 3 and 4, end members 5 and 6, and an intermediate member 7 extended between the members 3 and 4. The side members 5 and 6 are equipped with lugs 8 extended into the posts 1 and engaged by 50 screws 9, constituting part of any standard or desirable mechanism whereby the frame 2

considered as an entity, may be raised and lowered. In order to hold the frame 2 in any position to which it may have been adjusted vertically on the posts 1 a wedge-shaped key 10 is held for longitudinal reciprocation on the intermediate member 7, and is adapted to be advanced and retracted through the instrumentality of a screw 11, mounted for rotation but against endwise 60 movement in the side member 4, the inner end of the screw being threaded into the key 10 and the key being interposed between the intermediate member 7 and certain of the posts 1 as shown best in Figure 1 of the 65 drawings.

A slide 12 is mounted for horizontal reciprocation on the intermediate member 7 and a slide 14 is mounted for horizontal reciprocation on the end member 6 of the 70 frame 2. As shown in Figure 3 a horizontal shaft 15 is mounted to rotate in the slide 14, a stud 16 being mounted in the slide 12 in axial alinement with the shaft 15. A guide 17 is mounted to tilt for adjustment 75 on the stud 16, and a guide 18 is mounted to tilt for adjustment on the shaft 15. A carrier 19 is vertically adjustable in the guides 80 17 and 18. A post 20 is held in the carrier 19 clapper blocks 21 being pivoted at 22 upon opposite sides of the post 20 at the lower end thereof, the clapper blocks carrying cutters 23, the construction being such, as indicated in Figure 3, that when the work 85 moves in one direction, one of the tools will cut and the other tool will drag, whereas, when the direction of movement of the work is reversed, that tool which formerly was active, will become the dragging tool, whereas the tool which formerly dragged, will do 90 the cutting. The result is that a cutting is brought about upon each stroke of the work, as the work is carried backwardly and forwardly on the movable table of the planer. 95

A shaft 24 is journaled for rotation in the frame 2 and extends lengthwise of the intermediate member 7, the shaft being threaded into a projection 25 on the slide 12, as shown in Figure 3. Through the instrumentality of intermeshing beveled pinions 26, shown in Figure 1, the shaft 24 is connected operatively with a shaft 27 mounted to rotate on the side member 3. There is a beveled pinion 28 on the shaft 27, the same meshing with a beveled pinion 29 journaled 100 on the member 3 of the frame 2, a pinion 30 being mounted to rotate with the beveled 105 110

pinion 29. The pinion 30 meshes with a gear wheel 31 on a shaft 32 journaled on the frame 2 and extended lengthwise of the end member 6, the shaft 32 being threaded into the lug 38 on the slide 14. A ratchet gear 33, common in planers, is adapted to be mounted on the projecting end of the shaft 32 and meshes with a gear wheel 34 carried by a shaft 35 journaled in the member 3. A shaft 35 carries a pinion 36 cooperating with a rack bar 37 which is a known part of a common feeding mechanism in planers.

The rack bar 37 rotates the pinion 36, the pinion 36 rotates the shaft 35, from the shaft 35 rotation is imparted to the gear wheel 34, the gear wheel 34, cooperating with the ratchet gear 33, rotates the shaft 32, from the shaft 32, rotation is imparted by the gear wheel 31 to the gear wheel 30, the gear wheel 30 rotating the beveled pinion 29, the beveled pinion 29 driving the shaft 27 by way of the beveled pinion 28 and rotation being imparted to the shaft 24 by way of the beveled pinions 26. Recalling that the shaft 24 is threaded into the lug 25 on the slide 12 and that the shaft 32 is threaded into the lug 38 on the slide 14, it will be obvious that a means is provided whereby the tools 23 may be adjusted transversely of the line in which the work is being reciprocated.

The shaft 35 carries a gear wheel 39, meshing with a gear wheel 40 journaled on the member 3. A beveled pinion 41 is mounted to move with the gear wheel 40 and meshes with a beveled pinion 42 on a shaft 43 journaled in the member 3 of the frame 2 and located parallel to the shaft 27. On the inner end of the shaft 43 there is a beveled pinion 44 meshing with a beveled pinion 45 mounted to rotate with gear wheel 46 journaled on the member 3, the gear wheel 46 meshing with a gear wheel 47 on a shaft 48 journaled in the member 3, the shaft 48 carrying a gear wheel 49. The gear wheel 49 meshes with a ratchet gear 50 of the sort hereinbefore alluded to, the ratchet gear 50 being adapted to be mounted on a shaft 51 connected by any suitable mechanism of common and known construction, including beveled pinions 52, with a tool holder 53, to secure a vertical adjustment of the tool holder, the tool holder being mounted to reciprocate on a slide 54 carried by the member 5 of the frame 2. In the member 5 is journaled a shaft 55 threaded into a lug 56 on the slide 54. The ratchet gear 50 may be shifted to the shaft 55 when it is desired to secure a reciprocation of the slide 54 on the member 5 longitudinally thereof.

At the will of an operator the ratchet gear 33 may be shifted from the shaft 32 to a shaft 57 journaled in the member 6 of the frame 2 and extended longitudinally thereof. A beveled pinion 58 is splined to the shaft

57 to slide therealong at the will of an operator and is under the control of a lever 59, fulcrumed at 60 on the slide 14 and having an opening 61, adapted to be engaged with pins 62 on the slide 14, to hold the lever 59 in adjusted positions, the lever constituting means for shifting the beveled pinion 58 into and out of mesh with a beveled pinion 63 on the shaft 15, the shaft 15 being equipped at its inner end with a beveled pinion 64 meshing with a beveled pinion 65 held for rotation on the guide 18, a screw 66 being threaded into the pinion 65 and being held against longitudinal movement on the carrier 19. The screw 66 may be held against rotation, at the will of an operator, by a latch mechanism 67 of any desired construction. When the shaft 57 is rotated, rotation will be imparted to the shaft 15 by the beveled pinions 58 and 63, it being possible to disengage the pinions when the pinion 58 is moved through the instrumentality of the lever 59. When the shaft 15 is rotated, the pinion 65 will be rotated from the pinion 64, and the screw 66 will be caused to move vertically, thereby adjusting the carrier 19 and the tools 23 vertically. When the pinion 58 is disengaged from the pinion 63, the screw 66 may be rotated by hand to effect a raising and lowering of the carrier 19 and the tools 23.

The device hereinbefore described is relatively simple in operation, and the functions of the various parts have been set hereinbefore. It will be seen, however, that the tools 23 cut in opposite directions when the work is reciprocated and that it is possible to adjust the tools in various ways with respect to the work.

In Figures 5 and 6, a mechanism for operating the planer table is shown. In those figures, there appears a reversibly driven drive shaft 80 carrying a loose gear 81 and a fixed pinion 82, the pinion meshing with a gear 83 on a shaft 84 carrying a pinion 85 which meshes with the gear 81, the pinion 85 meshing with a gear 86 on a shaft 87 carrying a pinion 88 meshing with a gear 89 on a shaft 90. The gear 81 meshes with a pinion 92 on a shaft 91, the pinion 92 meshing with a gear 93 on a shaft 94 carrying a pinion 95 meshing with a gear 96 on a shaft 97. The rack bar of the planer table is marked by the numeral 98 and engages with the gears 89 and 96, rotation being imparted to the gears 89 and 96 from the reversibly driven shaft 80, and longitudinal reciprocation being imparted to the rack bar 98 and to the planer table from the gears 89 and 96.

What is claimed is:

In a device of the class described, pairs of posts, a frame mounted for vertical adjustment on the posts and means for adjusting the frame vertically on the posts, the frame comprising a first end member en-

- gaging the outer edges of the posts of one pair, a second end member engaging the inner edges of the posts of the other pair, an intermediate member disposed parallel to the end members and located between the pairs of posts, and side members located outwardly of the posts and connecting the extremities of the end and intermediate members; slides mounted for adjustment along the intermediate member and along the second side member, guides mounted to tilt for adjustment on the slides, a carrier adjustable vertically in the guides and including a post, and clapper blocks located at the lower end of the post and pivoted to opposite sides of the post, the post constituting an abutment for each clapper block when the same is in working position.
- In testimony that I claim the foregoing as my own, I have hereto affixed my signature in the presence of two witnesses.
